UNITED STATES PATENT OFFICE.

ADOLPH C. RECKER, OF OAKVILLE, CONNECTICUT, ASSIGNOR TO WATERBURY MFG. CO.,
OF WATERBURY, CONNECTICUT, A CORPORATION.

WEATHERPROOF PLURAL LAMP-SOCKET.

1,300,774.

Specification of Letters Patent. Patented Apr. 15, 1919.

Application filed June 16, 1917. Serial No. 175,146.

To all whom it may concern:

Be it known that I, ADOLPH C. RECKER, a citizen of the United States, residing at Oakville, in the county of Litchfield and 5 State of Connecticut, have invented a new and useful Improvement in Weatherproof Plural Lamp-Sockets; and I do hereby declare the following, when taken in connection with the accompanying drawings and 10 the characters of reference marked thereon, to be a full, clear, and exact description of the same, and which said drawings constitute part of this application, and represent, in—

15 Figure 1 a view in side elevation of a weather-proof plural lamp-socket embodying my invention.

Fig. 2 a plan view thereof.

Fig. 3 a view thereof in vertical section 20 on the line 3—3 of Fig. 2.

Fig. 4 a view of the metal parts as assembled prior to molding the body upon them.

25 Fig. 5 a detached perspective view of one of the closure disks.

Fig. 6 a detached perspective view of the plug.

Fig. 7 a detail broken view showing one 30 method of coupling the arms of the screw-plug shell and the arms of the lamp-receptacle screw-shells, together.

My invention relates to an improved plural or twin lamp-socket, the object being to produce at a low cost for manufacture, a plural lamp-socket constructed with 35 particular reference to being weather-proof, to durability, to smoothness of exterior finish, and to avoiding the use of assembling screws or nuts.

40 With these ends in view, my invention consists in a plural lamp-socket having certain details of construction as will be hereinafter described and pointed out in the claim.

45 In carrying out my invention as herein shown, I employ two lamp-receptacle screw-shells 4, 4, standing at an angle with respect to each other, made in one piece, having the adjacent edges of their upper ends 50 united by a web 5 and having the separated edges of their upper ends formed with coupling arms 6 located diametrically opposite the said web 5. The said arms 6 are formed with tongues 7 adapted to pass 55 through slots 8 in arms 9 depending at

opposite points from the screw plug-shell 10 which receives a plug 11 made of insulating material and having its upper end beveled as at 12 to project slightly beyond the contracted outer end 13 of the said 60 shell 10. The plug 11 is formed with a central longitudinal perforation 14 for the reception of a long contact-pin 15 formed at its outer end with a contact-head 16 bearing upon the projecting outer end of the 65 plug 11. The inner end of the contact-pin 15 passes through a perforation in the bowed upper end 17 of a bridge-piece 18. The lower ends 19 of the bridge-piece 18 are passed through radial slots 20 in heavy 70 closure-disks 21 located in the extreme inner ends of the shells 4. The said lower ends 19 of the bridge-piece 18 are transversely bent to form yielding contact-fingers 22 with which the contacts of the lamps are engaged. 75

The metal parts above described, having been previously assembled as shown in Fig. 4, are, with the exception of the screw plug shell 10, incased in a molded body 23 of 80 any suitable insulating material, which is applied plastic, under pressure so as to be forced into the substantially triangular space 24 produced by uniting the shells 4 with the shell 10 in the manner described. 85 The insulating material thus forced into the space 24, completely incloses the projecting inner end of the pin 15, the bridge-piece 18 and the coupling arms 6 and 9, whereby 90 they are permanently positioned with respect to each other against possible displacement and are also protected against breakage in any use of the socket, however rough. I should here call attention to the fact that the parts assembled as they are 95 shown to be in Fig. 4, are tied together as it were, against displacement when the insulating material in plastic form is applied to them, while the plug 10 and the closure disks 20 prevent the shells from being 100 crushed under the pressure of molding the plastic material. The disks 20 also prevent the plastic material from protruding into the lamp-receptacle screw-shells 4. The molded insulating body 23 as thus applied, 105 is seamless and so presents a smooth surface of attractive form, in addition to being of superior efficiency as a protective envelop, putting the socket in the weather-proof class. As shown, the lower ends of the body 110

where it incloses the shells 4, is molded with annular beads 25 for the retention of shade-holders of standard form.

I claim:—

- 5 In a weather-proof lamp-socket, the combination with a screw plug-shell and two lamp-receptacle screw-shells, of means for electrically connecting the said shells, slotted closure disks located within the inner ends
10 of the screw-shells, a contact pin passing through the said plug, contact-strips connected with the said pin and entering the slots in the said disks, and a one-piece molded body inclosing the said screw-shells and

filling the space between the said shells, 15 plug and disks, the said parts being assembled in spaced relation into a substantially unitary structure preparatory to the application of the molded body by which their spaced relations are permanently fixed 20 and they are protected.

In testimony whereof, I have signed this specification in the presence of two subscribing witnesses.

ADOLPH C. RECKER.
